(57) **CLAIM**

The ornamental design for a booster plate, as shown and described.

DESCRIPTION

FIG. 1 is a perspective view of a first embodiment of a booster plate showing our new design;

FIG. 2 is a top view of the booster plate shown FIG. 1;

FIG. 3 is a bottom view of the booster plate shown in FIG. 1;

FIG. 4 is a left-side view of the booster plate shown in FIG. 1;

FIG. 5 is a right-side view of the booster plate shown in FIG. 1;

FIG. 6 is a front view of the booster plate shown in FIG. 1;

FIG. 7 is a back view of the booster plate shown in FIG. 1;

FIG. 8 is a perspective view of a second embodiment of the booster plate;

FIG. 9 is a top view of the booster plate shown in FIG. 8;

FIG. 10 is a bottom view of the booster plate shown in FIG. 8;

FIG. 11 is a left-side view of the booster plate shown in FIG. 8;

FIG. 12 is a right-side view of the booster plate shown in FIG. 8;

FIG. 13 is a front view of the booster plate shown in FIG. 8; and,

FIG. 14 is a back view of the booster plate shown in FIG. 8. The broken lines in the drawings depict portions of the booster plate that form no part of the claimed design.

1 Claim, 14 Drawing Sheets
